UNITED STATES PATENT OFFICE

2,616,166

CAN OPENER

Arthur E. Inch, Phoenix, Ariz.

Application March 9, 1950, Serial No. 148,602

2 Claims. (Cl. 30—6.1)

1

This invention pertains to improvements in can openers and is particularly directed to an improved can opening mechanism for puncturing openings in the lid of the can.

One of the objects of this invention is to provide an improved can opener adapted to rapid and single hand operation.

Another object of this invention is to provide an improved perforating can opener which is safe and rapid in operation.

Still another object of this invention is to provide an improved can opener whereby the operator may simultaneously puncture the drain and air vent openings in the lid of a can.

It is also an object of this invention to provide an improved can opener which fastens to a wall or the underside of a table or counter top and which performs its operation by the single handed manipulation of the can into or out of the can opener.

Further features and advantages of this invention will appear from the detailed description of the drawing in which:

Figure 1 is a front elevational view of the can opener incorporating the features of this invention.

Figure 2 is a plan view of the can opener shown in Figure 1.

Figure 3 is a vertical section on the line 3—3 of Figure 2.

Figure 4 is a perspective view of the mounting bracket for the can opener.

Figure 5 is a perspective view of the swinging can supporting member.

As an exemplary embodiment of this invention there is shown an arrangement comprising a mounting bracket 10 having an upright portion 11 provided with screw holes 12 for mounting upon a wall or vertical support. Fixed to the member 11 is a horizontal plate portion 13 secured to the member 11 by suitable gusset plates 14 and 15 to make a rigid structure. The portion 13 is also provided with suitable mounting screw holes 16 so that it may be secured to the underside of a table or other horizontally disposed surface. Along the front edge of the portion 13 is a downwardly extending hinge portion 17 which supports a hinge pin 18 which extends outwardly on each side to form trunnions 19 and 20 upon which are journaled the bearing portions 21 and 22 of the U-shaped rocking member 23.

This rocking or swinging member 23 is provided with a U-shaped groove 24 having upper and lower sides 25 and 26 which nicely fit on each side of the rim of the can to be opened. Preferably

the outer ends of the U-shaped groove 24 are made divergent at 27 and 28 to facilitate placement of the can in the U-shaped groove 24. The U-shaped member 23 is confined or limited in its swinging motion from the position 23a to the opening or perforating position 23b. In the loading and unloading position for the cans to be opened at 23a the surface 29 of the member 23 engages the turned up abutment edge 30 formed on the portion 11 of the bracket member 10. Normally the U-shaped member 23 remains in the position 23a by gravity during the loading and unloading of the can from the can opener.

The portion 13 of the mounting bracket 10 is provided with a pair of downwardly extending sharp perforating points 31 and 32 which enter into and are directly above the U-shaped opening formed by the groove 24. Preferably, the points 31 and 32 are located closely adjacent to the outer rim of the lid of the can.

In the operation of the can opener the operator merely grasps the can in one hand around its cylindrical body portion 31 and moves the top bead into the divergent guideways 27 and 28 and forces it further inward until the can arrives in the U-shaped groove 24 as best shown in Figure 3. The can is then forced in backward tilting position 31a causing the perforating prongs 31 and 32 to simultaneously puncture both the drain opening 30 and the air inlet opening in the lid of the can. The can is then tilted backwardly to the position 31b and slid out of the U-shaped groove 24 ready for use. Thus by single manipulation with one hand of the can 31 both the necessary drain and air inlet perforations are made in the lid 32 of the can so as to facilitate ready emptying of the contents thereof.

Having thus fully described this invention what is claimed is:

40. 1. A can opening device comprising an L-shaped bracket having vertical and horizontal mounting surfaces, can lid perforating prongs fixed on the horizontal portion of said L-shaped supporting bracket, a hinge portion on said front 45 portion of said bracket adapted to pivotally mount a U-shaped can engaging member, a bead engaging groove formed in said U-shaped member, and divergent entrance slots connected to the outer ends of said U-shaped groove and carried in said U-shaped member.

2. A can opening device comprising an L-shaped bracket having vertical and horizontal mounting surfaces, can lid perforating prongs fixed on the horizontal portion of said L-shaped 55 supporting bracket, a hinge portion on said front

portion of said bracket adapted to pivotally mount a U-shaped can engaging member, a bead engaging groove formed in said U-shaped member, and divergent entrance slots connected to the outer ends of said U-shaped groove and carried in said U-shaped member and stop means on said supporting bracket member for limiting the pivotal motion of said U-shaped member.
